CLOCK

Leo I. Bruce, Framingham Center, Mass., assignor to
General Electric Company, a corporation of New York

Application December 14, 1954, Serial No. 33,536

Term of patent 7 years

(Cl. D42—7)

Fig. 3

Fig. 1

Fig. 2

To all whom it may concern:

Be it known, that I, Leo I. Bruce, a citizen of the United States, residing at Framingham Center, in the county of Middlesex, Commonwealth of Massachusetts, have invented a new, original, and ornamental Design for a Clock, of which the following is a specification, reference being had to the accompanying drawing, forming a part thereof.

Fig. 1 is a top plan view of a clock showing my new design.

Fig. 2 is a front elevational view of the clock.

Fig. 3 is a side elevational view of the clock.

I claim:

The ornamental design for a clock, substantially as shown.
